UNITED STATES PATENT OFFICE.

CLEVELAND J. WILKINSON, OF VENTURA, CALIFORNIA.

TRAVELING BLOCK.

Application filed December 12, 1922. Serial No. 606,553.

This invention relates to blocks, and particularly to traveling blocks such as used for lifting drill pipe used with the rotary system of oil well drilling. The invention has for an object the provision of a traveling block which incorporates novel features of construction relating to the oiling of the moving parts of said block, as well as the provision of a block that will not tangle with casing lines or turn over so as to release the hook associated with said block and drop any well casing carried by the block.

With the above and other objects in view, the invention consists in the novel and useful provision, formation, construction and inter-relation of the various parts, members and features, all as disclosed in the accompanying drawing, described in the following statement, and finally pointed out in claims.

In the drawing:

Figure 1 is a fragmentary perspective view of the improved block shown in position of service;

Figure 2 is a fragmentary side elevation of the improved traveling block;

Figure 3 is a cross sectional view of the traveling block, taken on the line 3-3 of Figure 2, and looking in the direction of the appended arrows; and,

Figure 4 is a fragmentary end view of a certain feature of the traveling block.

Corresponding parts in all the figures are designated by the same reference characters.

At the present time traveling blocks are so constructed that the pintle carrying the sheaves as well as securing members for the shell extend beyond the traveling block shell. Securing means are joined with the pintle so that the same may not slip from the shell and dislodge the sheaves therefrom. However, these external obstructions on the shell tend to come into contact with tool joints and pick up the stand pipe or throw it out of position in such a manner that one may drop through the derrick floor with disastrous results. It may also happen that when rope is rove about the sheaves the block may turn over in the lines or rope due to certain of the pipe hanging up while running of other pipe into the well hole. If

this occurs the line may jump the groove in certain of the sheaves and wedge between the sheave and the side of the block, cutting the line in two and thus dropping the pipe. Traveling blocks at present are likewise constructed with bushing members between the sheaves and the pintle upon which the sheaves run, and when the bushing members become worn they start traveling in the sheave. As the oiling system is usually through the pintle, traveling movement of the bushing will immediately render the oiling system of little use, with the result of burnt-out bushings, which at times become so hot as to cause a fire in the derrick, or necessitates shutting down the plant until new bushings or new sheaves are placed in the block. My invention tends to overcome all these faults by providing a traveling block in which the shell on the exterior thereof is free from obstructions, therefore preventing the pulley from hanging up on tool joints or in any way picking up stand pipe. My invention also contemplates the provision of means for preventing the line from becoming dislodged from any one of the sheaves and wedging as between a sheave and the shell, and therefore will prevent the line from being cut in two. Furthermore, with my pulley block I so arrange the bushing that the same may be keyed to the sheaves and thus prevent the bushing from traveling independently of the sheaves. This ensures that the oiling system will at all times function.

Referring with particularity to the drawing the improved block is designated in its entirety by A, of which *a* is the shell, *b* sheave members within said shell, *c* means for preventing jumping of the line *d*, adapted to be rove about the sheaves, and *e* and *f* loops associated with the shell. A pintle or axle *g* passes through aligned openings in sides 1 and 2 of the shell *a*. In this particular the sides 1 and 2 of the shell swell toward their median portions, as illustrated at 3, and the side 2 is provided with a tapered bore or opening 4 at the enlarged or swell portion 3. The pintle *g* is provided with an enlarged end 5 which is likewise tapered to fit within the taper opening 4 of the side 2. The side 1 at the enlarged

portion 3 is provided with a circular recess 6 adapted to receive a bolt head 7, the screw-threaded shank 8 of said bolt head passing through an opening 9 in the side 1, 5 and having a screw-threaded engagement with a portion of the pintle *g*, as illustrated at 10. The pintle *g* is provided with a longitudinal bore 11 and transverse bores 12 communicating with the bore 11. The shank 8 of the bolt is likewise provided with a longitudinal bore and with transverse bores 13 communicating with said longitudinal bore. The side 1 of the shell *a* is provided with a bore communicating with one of the transverse bores 12 in the pintle and within the bore in the shell side 1 is received a tube 14. The general direction of the bore in the shell side 1 and the position of the tube 14 is illustrated in Figure 2 by dotted lines. 10 Oil may be placed within the tube 14 and the oil will flow through the transverse bore 12 into the oil openings 13 of the bolt shank, and thence through the longitudinal opening in said shank into the bore 11 of the 15 pintle and from thence through the transverse bores 12 in said pintle. This will ensure an oiling as between itself and a series of bushing members *h*. The sheaves *b* are directly associated with the bushings *h* and 20 keyed together. The keying arrangement with the bushings and the sheaves is illustrated in Figure 4, and said keying is accomplished by giving each bushing and each sheave at its cooperative portion a half bore, 25 the two halves cooperating for the reception of a pin 15. As shown in Figure 4, a series of keys are arranged at different points between the bushing and the sheave. This keying is repeated for each sheave with its 30 bushing. The bolt head 7 is curved on its exterior surface so as to be smooth and in alignment with the remaining surface of the shell side 1. The shell sides at their ends are triangular shaped as illustrated in 35 Figure 2, and the top portion of each side cooperates in the forming of the upper loop *e*, as illustrated at 16 in Figure 1. The means *c* for keeping rope or line rove about each sheave, may consist of a plurality of 40 spaced partitions 17 and 18 interposed between webbings 19 separating each sheave, and the partitions 17 and 18 are maintained spaced by collars 20, the said partitions and 45 collars being carried upon a rod or pin 21. Figure 2, and the top portion of each side cooperates in the forming of the upper loop *e*, as illustrated at 16 in Figure 1. The means *c* for keeping rope or line rove about each sheave, may consist of a plurality of 50 spaced partitions 17 and 18 interposed between webbings 19 separating each sheave, and the partitions 17 and 18 are maintained spaced by collars 20, the said partitions and 55 collars being carried upon a rod or pin 21. This rod is similar in shape to the pintle *g*, in that it has one end thereof enlarged and tapered as shown at 22 for reception in a correspondingly tapered bore 23 in the side 2. The other end of said rod is received 60 in an enlarged opening 24 in the side 1, and the rod is provided with a screw-threaded bore 25 for reception of a screw-threaded shank 26 of a bolt 27. The head 28 of the bolt 27 is received within a circular recess in 65 the side 1, as illustrated at 29, so that the exterior surface of the side 1 will be free of any obstruction. The webbings 19 extend downwardly to and beyond the pintle *g*, as shown in Figure 3. The end 30 of the shell *a* carries the swinging loop *f* and as before, a rod or pin 21 is carried by the sides 1 and 2 of the shell *a*. As the opening in the shell sides and the general shape and structure of the rod is similar to the rod just described, the same reference characters will be applied to the end 30. However, in place of certain of the collars 20, the loop *f* is carried by the rod 21, as illustrated at 31. In the construction shown three sheaves are provided and the middle spacer 20 is retained as between the partitions 17 and 18. The loop *f* is likewise provided with wing portions 32 and 33 so that the sides of the hook are substantially flush with the sides of the shell. The bolt heads 7 and 28 are each bored for reception of a small screw 34 having screw-threaded engagement in the side 1 of the shell for the purpose of preventing said screw from turning. 70 75 80 85 90 95 100 105 110 115 120 125 130

The operation of the device is no doubt obvious. However, referring to Figure 1 the loop *f* will carry a pulley block hook *k*, and the loop *e* will have attached thereto one end of the line *d*. Other lengths of the line *d* are rove about the sheaves *b*, and it will be noted that if for any reason the pulley block should get turned sideways the line *d* would be received as between the grooves in said sheaves and the partitions 17 and 18, which would direct the line back into the grooves of the sheaves. Furthermore, the exterior surface of the shell is free from all obstructions, so that the same may readily pass other lines and cannot be hung up on tool joints. The oiling system is positive, inasmuch as the bushings are keyed to the hubs of the sheaves so that the said bushings must at all times turn with the sheaves. 110

It is obvious that various changes, modifications and variations may be made in practicing the invention, in departure from the particular description as given, and the showing in the drawing, but that said changes may be made within a fair interpretation of the invention as set forth in the appended claims. 115

Having thus disclosed my invention, I claim and desire to secure by Letters Patent: 120

1. A traveling block including a shell, a pintle carried by said shell, and sheaves upon said pintle; said shell having one of its sides provided with a taper bore and the said pintle having a portion thereof enlarged and tapered for reception in said taper bore, the end of the enlarged portion of said pintle and the outside of said shell presenting a flush surface, and means for maintaining said pintle within said shell, said 125 130

means comprising a bolt received in the opposite side of said shell, the head of which bolt is flush with the surface of said side of the shell.

5. 2. A traveling block, including a shell, a fixed loop member at one end of said shell and flush with the outer sides of said shell,

a second loop member swingingly carried at the opposite end of said shell, said swinging loop member being formed to have a flush 10 surface with the outer sides of the shell.

In testimony whereof, I have signed my name to this specification.

CLEVELAND J. WILKINSON.
